LOCKING ELEMENT FOR MOUNTING ELECTRONIC TERMINALS AND THE LIKE

James V. Murphy, 100 Sherwood Ave., Warwick, R.I.

Filed Apr. 8, 1963, Ser. No. 74,324

Term of patent 14 years

(Cl. D54—9)

Fig. 1

Fig. 2

Fig. 3

Fig. 4

Fig. 5

FIG. 1 is a front elevational view of a locking element for mounting electronic terminals and the like showing my new design;

FIG. 2 is a side elevational view thereof;

FIG. 3 is a rear elevational view thereof;

FIG. 4 is a sectional view taken on line 4—4 of FIG. 1; and

FIG. 5 is a greatly enlarged fragmentary sectional view illustrating the configuration of the knurling.

I claim:

The ornamental design for a locking element for mounting electronic terminals and the like, substantially as shown.
